United States Patent Office

Des. 207,922
Patented June 13, 1967

207,922

BOTTLE

John S. Frazer, Fair Lawn, N.J., assignor to Union Carbide Corporation, New York, N.Y., a corporation of New York

Filed Sept. 21, 1964, Ser. No. 81,818

Term of patent 14 years

(Cl. D58—6)

Fig. 1.

Fig. 2.

FIG. 4.

FIG. 3.

FIG. 1 is a front and side perspective view of a bottle embodying my new design;

FIG. 2 is a top plan view thereof;

FIG. 3 is a side elevational view, the opposite side being a mirror image of the side shown; and

FIG. 4 is a rear elevational view thereof.

The dominant features of my design reside in the portions shown in full lines.

I claim:

The ornamental design for a bottle, substantially as shown and described.
